UNITED STATES PATENT OFFICE.

JOHN AUSTIN BEST, OF AUGUSTA, GEORGIA.

FILING SYSTEM.

1,065,206.

Specification of Letters Patent. Patented June 17, 1913.

Application filed December 5, 1911. Serial No. 664,058.

To all whom it may concern:

Be it known that I, JOHN AUSTIN BEST, a citizen of the United States, and a resident of Augusta, in the county of Richmond 5 and State of Georgia, have invented a new and Improved Filing System, of which the following is a full, clear, and exact description.

My invention relates generally to filing 10 systems and more particularly it is directed to an improved system wherein the successive cards held therein are so arranged that facial portions of each are visible, thereby enabling the cards to be distinguished from 15 each other and selected in a short space of time.

A further object of the invention is to provide an index card of particular construction having suitable perforations thereon, 20 the perforations being adapted to coöperate with suitable fastening devices whereby a plurality of the cards may be held together with the upper or side portion of each exposed in order to disclose a name or other 25 information set forth on the card.

A further object of the invention is to provide a filing system made up of a suitable cabinet having a longitudinally extending member therein or a plurality of such members, 30 together with a number of cards having similar perforations along one edge or opposite edges which coöperate with the said rod or rods whereby the cards are held in position within the cabinet with a portion 35 of each exposed and in position for quick withdrawal.

Other objects and advantages of the invention will appear as the description thereof proceeds, all of which is particularly 40 pointed out and included in the appended claims.

Reference is to be had to the accompanying drawings forming a part of this specification, in which similar characters of reference 45 denote corresponding parts in all the views, and in which—

Figure 1 is a vertical sectional view of a cabinet embodying my invention; Fig. 2 is a vertical sectional view thereof on the line 50 2—2 of Fig. 1; Fig. 3 is a sectional view on the line 3—3 of Fig. 1 showing the means whereby the longitudinal rods are actuated; Fig. 4 is a vertical sectional view similar to Fig. 2 but showing a modified arrangement 55 in that only one rod is used and that a plurality of adjacent portions of each card are

visible; Fig. 5 is a partial front view of the cabinet showing the underlying locking means for holding the rod of Fig. 4 in position; Figs. 6 and 7 are front and side views 60 respectively of a number of cards similar to those shown in Figs. 1 and 5 but designed to be held together by means of a rubber band whereby they may be disposed of in any suitable cabinet or carried about in the 65 pocket; Figs. 8 and 9 are similar views showing cards with a slightly different form of notches or recesses along the opposite sides especially adapted for use with a common form of fastener; Figs. 10 and 11 are similar 70 views of a number of cards arranged similarly to those described, each card, however, being provided with a pocket into which an auxiliary card may be fitted; Fig. 12 is a sectional view on the line 12—12 of Fig. 10; 75 Fig. 13 is a plan view of a number of similar cards held in position with the top portion of each exposed, the cards being provided with a suitable backing; Fig. 14 shows a convenient arrangement in book form; Fig. 80 15 illustrates in horizontal section a modified form of the box and rod arrangement shown in Fig. 1; Fig. 16 illustrates a modified form of the arrangement shown in Fig. 4; and Fig. 17 is another modification to be herein- 85 after specifically described.

Referring particularly to Figs. 1 and 2, the cabinet may be of any suitable size or shape and may be made of any desirable material, being preferably in the form of a box 90 having the top side thereof open, the cabinet being made up of the front and rear members 1, 2, the sides 3, 4, the bottom 5. Extending longitudinally of the cabinet are a plurality of rods 6, preferably rectangular 95 in cross section, one end of each of the rods being mounted in suitable bearings 7, contained within one of the end members 2, there being suitable bearings 8, contained within the front member; in order to provide a convenient construction wherein many of the underlying parts will be covered, the front of the index may be conveniently made in two parts 1^a, 1^b, as shown particularly in Fig. 1, the advantage and 100 utility of such construction to be hereinafter described.

Each of the cards 9 is apertured along opposite sides, the apertures being in the form of a plurality of similar openings 10, these 110 openings being preferably circular in shape and spaced a suitable distance from the op-

posite edges of the card, and recesses 11 extending inwardly from the edges and communicating with the openings. The diameter of each of the openings 10 is substantially equal to the width of each rod 6 while the width of the recesses 11 is substantially equal to the thickness of each rod 6 so that when the cards are positioned as shown in Fig. 2 they are firmly secured on the rods, turning of the rods 90°, however, permitting each card to be slipped off the rods, the rods passing through the recesses 11.

In order to actuate both rods simultaneously when it is desired to insert or remove cards, I make use of the structure shown particularly in Figs. 1 and 3; the section 1^a of the front end 1 of the cabinet is provided with a suitable recess 12 on its rear face and extending a sufficient distance 20 thereacross within which the arms 13 carried by each of the rods 8 extend, the lower ends of these arms being connected by a rod 14, one of the rods being extended through the outer section 1^a and terminating in a 25 suitable actuating device, such as a thumb nut 15. In order to maintain the locked or unlocked position of the rods a spring 150 is provided, one end of the spring engaging the rod 14 and the other end thereof being secured within the recess 12; a device similar in function is shown in Fig. 5 and may be used if so desired, either rod 6 being provided with a suitable enlarged portion 17 having notches 17^a, 17^b, therein, either of 30 which is adapted to be engaged by the hooked end 18 of a leaf spring 19 suitably secured in position to the front member at 20. Thus it will be observed that turning of one rod is communicated to the other rod 40 by the connection stated whereby both sides of the cards are secured or unsecured at the same time, the engagement between either notch 17^a, 17^b, and the end of the leaf spring 19 in the construction shown in Fig. 5 holding the rods against accidental displacement. 45

It is to be noted that the apertures along the opposite sides of the cards shown in Figs. 1 and 2 are similar to each other and that these apertures are transversely alined, 50 the distance between any two of the apertures on either side of the card being the same as the distance between any other two. By such an arrangement I am enabled to arrange the cards as shown in Fig. 1 where- 55 in three packs are shown being held in inclined position by means of a follower board 16 having an inclined front face, each of the packs being separated by means of suitable division cards 17; the rods 6 are en- 60 gaged in holes number 10 of the card 9^a, in holes number 9 of the card 9^b, in holes number 8 of the card 9^c, and so on until, as in this instance, ten cards are formed into one pack. This arrangement of the cards on the 65 rods provides for a given distance along the

upper portion of each card to be visible when the cards are in the cabinet, this distance at the top being sufficient to set forth any convenient data such as names, addresses, etc. The number of packs in the 70 cabinet will depend primarily on the size of the cabinet or the length thereof, the size of each card depending upon the matter to be set forth thereon, the arrangement of the several cards, however, affording a simple 75 and convenient construction wherein it is unnecessary to separate each card from the others in order to learn what is on the card.

Referring particularly to Fig. 4 the cabinet is shown provided with a single longitudinally extending rod 6^a along an intermediate portion thereof and adjacent the bottom, the rod being actuated preferably by the means already described; in this instance each of the cards 9' is apertured along 80 one side only, the apertures being similar to those before described and including inner openings 10 communicating with the outer edge of the card through recesses 11. In this instance the width of each card is substantially less than the width of the cabinet, the cards arranged in succeeding packs similar to that shown in Fig. 1, the distinction, however, lying in the provision of the visible portions of the cards along the sides, as 85 at 9^d, and also at a tapered portion 9^e intermediate these sides and the tops. It is to be noted that while in Fig. 1 the top of each card in each pack is at a different elevation than the other cards in the pack that the 90 width of each pack within the cabinet is the same while in Fig. 4 the height of each pack within the cabinet is the same, the cards of each pack being differently arranged and disposed so that their side edges lie in different vertical planes. This form of device 95 may be preferable to that shown in Figs. 1 and 2 in some instances, the inventive idea, however, being the same in each case, and the cards being positioned within and removed from the cabinet by operation of the single rod 6^a in very much the same manner as that previously described.

In Figs. 6 and 7 I have shown a number of cards 20 having apertures in the form of 100 notches 21 at the sides thereof, the notches being equally spaced, the cards being arranged to be held in a pack by means of a suitable band 22, the band engaging a notch at each side of each card, as shown in Fig. 105 7, whereby a convenient outfit is provided which may be easily removed from the cabinet and placed in the pocket if so desired.

In Figs. 8 and 9 the cards 30 are provided with rectangular notches 31 equally spaced, the cards being held together by a fastener 32 comprising bent metal clips, the fastener engaging a notch on each succeeding card and at opposite sides whereby the 110 top portion of each succeeding card is made 115

visible, together with any data or names that may appear thereon.

In Figs. 10, 11, and 12, I have shown a structure embodying the principles already described, each of the cards, however, being provided with a pocket 45 adapted to receive a separate card 46 of a size adapted to the pocket, the top portion of each pocket being at a higher elevation than the one before it, 5 all of the cards 40 which contain the pockets being provided along opposite sides with suitable cuts 41 adapted to receive a fastener 42 of well-known construction; in this instance each card may be withdrawn from 10 each pocket without disturbing the cards in the other pockets or without the necessity of removing the fasteners 42 in order to render the whole of each card 40 visible. Of course, this construction embodying the pockets 15 with the cards removable therefrom may be used in connection with a suitable cabinet or drawer, the packs being positioned successively therein and being conveniently removable therefrom since it is often desirable 20 to remove a number of cards and keep them out for some time.

In Fig. 13 each card 50 is provided with a series of vertical cuts 51, along one side thereof, the cards being held one above the 25 other with the top portion of each exposed by suitable fastening devices 52 engaging cuts in each of the cards, all of the cards which, in this instance, may be made of thin paper being secured to a suitable backing 53 of stiff or heavy material in order to provide 30 a support when writing on the card. This arrangement is very much like the leaves of a book and each of the cards swings to one side about the fasteners 52, thereby making 35 the whole of each card accessible if it is desired to enter any data thereon.

The structure shown in Fig. 13 may as 40 shown in Fig. 14 be provided with a backing 53^a, 53^b, similar in character to the backing 45 53 just described on opposite sides thereof whereby the cards are protected, the resulting structure being book-like, one of the covers being movable relatively to the cards in the other cover in order to enable each 50 card to be gotten at; if so desired, in this instance, the opposite sides of the cards may be provided with the cuts 51', the cards being secured in position at each side by fastening devices 52'.

55 In Fig. 15 I have shown a modification of the cabinet illustrated in Figs. 1 and 2, wherein such a device is made up of the sides 3^a, 3^b, the ends 1^a, 2^b, and the bottom 5^a; in this instance the ends are provided 60 with similar openings 7^a, 7^b, designed to receive a rotatable rod 6^a, preferably of rectangular construction, the front end of the rod being provided with a suitable winged nut 15 similar to that shown in Fig. 1; the 65 ends are also provided with openings 7^c, 7^d,

at a suitable distance from the openings 7^a, 7^b, which openings receive a similar rod 6^a, the front end of which is provided with a winged nut 15, the rods in this instance being designed to be withdrawn a suitable distance or entirely from the cabinet so that the latter may be more conveniently filled with, or emptied of, its cards or packs of cards. The rods 6^a engage with similar perforations at opposite sides of the parts so that the resulting arrangement is substantially similar to what is shown in Fig. 1. 70 75

In Fig. 16 a cabinet similar to that shown in Fig. 4 is illustrated and is designed to hold the cards 9' in a manner similar thereto; in place of the rotatable rod 6^a; however, I make use of an equivalent structure in the form of an upstanding element 6^b designed to enter suitable notches 100 contained along one side of the cards, the depth of which is 80 substantially equal to the height of the element 6^b. This upstanding element is conveniently formed from a single piece of material of rectangular construction bent along an intermediate part to form this element, 85 the remaining portions of the material being of a size sufficient to form a lining 5^b at the bottom of the cabinet. The manner of use of the cards shown in Fig. 16 in connection with this cabinet is essentially the same 90 as what has been originally described, the distinction lying not in the idea involved but in the particular means whereby the idea is made practical. 95

It is desirable in some instances that the 100 card records be taken from the cabinet in which they are placed for use elsewhere for a certain length of time and in order to provide a convenient and simple way of protecting and taking care of the cards when 105 so removed, as well as facilitating the use of the cards, I have shown, in Fig. 17, a device embodying a book made up of the covers 90 provided along an intermediate portion with a number of rings 91 made up of a plurality 110 of parts movable relatively to each other in any desirable manner, the cards being provided along one edge with a number of apertures in the form of perforations 92 adapted to be engaged with these rings, different 115 perforations in different cards engaging different rings; whereby the end portions of the cards are visible when they are inclosed within the book. In illustrating this use of the invention I have shown particularly the 120 cards illustrated in the cabinet of Fig. 16, the convenience with which the cards may occupy their proper positions in each of the devices being apparent. The cards shown in Fig. 16 and on the left hand side of Fig. 125 17 are substantially the same, as far as the exposed end portions are concerned, as those shown in Fig. 4; it is clear, however, that the cards may be exposed only along the top portion, as shown on the right hand side of 130

Fig. 17, such arrangement being similar to what is shown in Figs. 2, 6, 13, and 14.

In the use of my invention and the reduction of the idea to practice with different businesses or methods of keeping account, it is obvious that cards of different colors and different shapes may be used in order to indicate certain facts, it being also clear that a complete system involving the use of 10 the cards and the method herein shown may be standardized so that cards transferred from the cabinet of one department may be inserted in their proper places in the cabinets of other departments without necessitating 15 changes in such cabinets or transferring the data on the cards to other cards.

From the above description taken in connection with the accompanying drawings it will be observed that the inventive idea of 20 this application involves the use of a number of cards of similar construction held together by suitable means with the top portion 25 of one face of each card always visible, whereby any names or other information appearing thereon may be visible.

Of course the material of which each card is made and the sizes of the cards and the particular shape of the notches or openings therein may be such as is best suited to the 30 purpose, such changes being included within the spirit and scope of the appended claims.

Having thus described my invention, I claim as new, and desire to secure by Letters Patent:—

35 1. The combination of a plurality of cards having similar apertures along one side thereof, with a fastening means engaging an aperture in each card, the aperture in each successive card so engaged being nearer one 40 end of the card than in the adjacent card.

2. The combination of a plurality of cards having a number of similar apertures along opposite sides thereof, with a fastening device for holding the cards together, the said 45 device passing through an aperture in each card, the apertures so engaged in successive cards being at different distances spaced from the ends thereof than those in the adjacent cards.

50 3. The combination of a plurality of cards having apertures along one side thereof, with a fastening device engaging one aperture in each card, whereby they are held together, the apertures so engaged being at different 55 distances from the ends of the cards, whereby a portion of each card is visible.

4. The combination of a plurality of cards having apertures along one side thereof, the apertures being equally spaced, with a fastening device engaging all of the cards and 60 passing through an aperture in each card, the said device being at unequal distances from the ends of the said cards.

5. The combination of a suitable cabinet having a rod therein, with a plurality of 65 cards each having a number of apertures along one side, one of said apertures in each card engaging the rod, the said cards being arranged successively with the end portion of one card extending beyond the end portion of the preceding card, whereby the end portions of all the cards are visible.

6. The combination of a suitable cabinet having a rod extending therethrough, with a plurality of cards arranged in separate 75 packs, each of the cards being similar to every other one and being provided with a number of apertures along one side, the rod engaging an aperture in each card, the end portions of the cards in each pack being 80 visible.

7. The combination of a suitable cabinet having a plurality of rods therein, a plurality of cards within the cabinet, the cards being arranged in packs, each card being 85 provided with a plurality of apertures along opposite edges thereof, the rods engaging opposite apertures in each card, the top portions of successive cards being at a higher 90 elevation than the preceding cards in the same pack whereby a portion of each card is visible.

8. The combination of a suitable cabinet having a plurality of rods therein, each of the rods being rectangular in cross section, 95 a plurality of cards arranged in packs contained within the cabinet, each of the cards being provided with apertures along opposite sides, each of the said apertures consisting of a recess and an opening, the width 100 of the opening being substantially equal to one dimension of the rod and the diameter of the recess being substantially equal to the other dimension of the rod whereby the cards may be placed on the rods when the rods are in one position, turning of the rods to a second position locking the cards 105 thereon.

9. The combination of a suitable cabinet having a plurality of rods rotatably supported thereon, with a number of packs of 110 cards placed on the said rods, each pack comprising a number of cards provided with apertures along their opposite sides, certain 115 of said apertures engaging the rods, the top portions of the cards in each pack being at unequal distances above the rods whereby the top portions of such cards are visible.

In testimony whereof I have signed my name to this specification in the presence 120 of two subscribing witnesses.

JOHN AUSTIN BEST.
